UNITED STATES PATENT OFFICE.

MAX ROCKSTROH, OF KLEIN-SEDLITZ, NEAR PIRNA, GERMANY.

SAFETY DEVICE FOR PLATEN PRINTING-PRESSES.

1,018,005.

Specification of Letters Patent. Patented Feb. 20, 1912.

Application filed May 17, 1911. Serial No. 627,656.

To all whom it may concern:

Be it known that I, MAX ROCKSTROH, director of a company, a citizen of the Kingdom of Saxony, residing at Villa Lützow, 5 Klein-Sedlitz, near Pirna-on-the-Elbe, Germany, have invented certain new and useful Improvements in Safety Devices for Platen Printing-PresSES, of which the following is a specification.

10 This invention relates to a safety device for platen printing presses operating on the interruption of the movement of the roller carriage.

On printing with platen printing presses 15 it often occurs that the roller carriage catches on projecting types or packing or spacing material, or that the regular working of the roller carriage is interrupted by paper waste or sheets of paper which have 20 adhered to the rollers. It may thus occur that the roller carriage is flattened between the printing form and the platen, or that some part adapted for the movement of the roller carriage is broken. According to the 25 present invention such accidents due to the interruption of the regular working of the roller carriage are prevented by a machine part which assists in transmitting the movement and effects the release of stop mechanism, on any braking action or fracture occurring thus automatically putting the press 30 out of operation and applying the brake.

In the accompanying drawing Figure 1 is a platen printing press in side elevation 35 partly in section provided with the stopping mechanism, under the conditions of the normal working of the press. Fig. 2 shows the stoppage of the roller carriage and the press out of operation. Fig. 3 shows a front elevation of the platen printing press with the parts in question. Figs. 4 and 5 show a constructional form of the machine part, consisting of two members which on the 40 stoppage of the roller carriage alter their position in relation to one another, and throw the press out of operation. Fig. 6 is a side elevation of a platen printing press provided with a modified form of safety device in plan. Fig. 7 shows a rear elevation 45 of the same arrangement. Fig. 8 is a section on the line α — α Fig. 6.

In the constructional forms illustrated the connecting rod, which causes the upward and downward movement of the lever of the 50 roller carriage, is employed for effecting the

stopping of the machine. For this purpose the connecting rod, according to Figs. 1, 2 and 3, consists of two members 7 and 8 which engage with each other by means of grooves, prisms or wedges, and are pressed together by means of a spring 10 during the uniform movement of the roller carriage. If, however, in consequence of a fracture or stoppage greater forces arise, the spring, which presses the members of the connecting 60 rod together, is no longer capable of resisting and the parts slide over one another. The connecting rod therefore shortens or lengthens according to the direction of the forces which occur and the displacement of 65 the members of the connecting rod causes the release of the check action of the disconnecting rod.

1 indicates the roller carriage, which in the known manner is moved upward and 70 downward by the rod 2 through the medium of the roller carriage lever 4. The connecting rod consists of the two members 7 and 8 held pressed together by means of grooves and projections in consequence of the pressure of a spring 10 placed around the bolt 9. On the pivot 17 is rotatably mounted a bell crank lever 16 which during the regular operation of the press assumes the position shown in Fig. 1, in view of the fact that 75 it engages by a knife-like lateral projection 18 provided at the upper end of one of its arms with a similar projection 20 provided on the connecting rod member 7. On the slightest prolongation or shortening of the 80 connecting rod by the variation in position in relation to one another of the members 7 and 8 of the connecting rod, the two knife edges 18 and 20 slide from one another. Against the other arm of the bell crank lever 16 rests a pin 15 provided on a lever 14 which is rotatable on the shaft 3. The lever 14 is under the action of a spring 19 and retains its normal position as long as 85 the knife-like projections 18 and 20 are in 90 engagement with one another. When forces arise which release the members 7 and 8 of the connecting rod from one another then the connecting rod is either lengthened or 95 shortened. In consequence of this the knife edge 18 of the lever 16 slides from the knife-edge 20 of the connecting rod member 7, the lever 16 rotates and allows the lever 14, which is under spring action and engages 100 therewith by means of the pin 15 to rotate 105 110

also and to strike against the end of the weighted bell crank lever 28 and thus raise the pawl 27 from the projection 24 whereby the latter in consequence of the action of 5 the spring 25 suddenly puts the press out of operation and applies the brakes. The position of this lever when the press is out of operation is shown in Fig. 2.

Figs. 4 and 5 show a further constructional form of the connecting rod. This is also in two parts and consists of the connecting rod members 11 and 12, which are connected together by means of pins 13. The resistance of these pins is such that during 15 regular working they remain in position but on greater forces arising they effect a lengthening or shortening of the connecting rod.

In the constructional form shown in Figs. 20 6-8 the parts of the rod, which move the roller carriage, are integral with, and form an unstable intermediate member connected thereto of which the variation in length puts the press out of operation. In an arm 40 25 connected to the roller carriage is rotatably mounted a three-armed lever 29, 37 and 38 to the short arm 37 of which is connected the connecting rod 2 which is moved upward and downward, in the known manner by the 30 lever 4. The upwardly projecting arm 38 of the three armed lever 29 is provided with a groove 42 with which engages a spring bolt 30 which is mounted in the guide 43 of the carriage 1 and thus retains the three 35 armed lever in its normal position. The downwardly projecting arm of the lever 29 engages with its forked end (Fig. 8) with a rib 31 of a rotatable spindle 39 mounted in bearings 32 and 33, the length of said 40 rod corresponding to the travel of roller carriage. At the lower end of the spindle 39 is provided an arm 34 which locks the bell crank lever 35. The bell crank lever is under the action of a spring 19 which 45 tends to rotate it about its fulcrum 36; its lower arm projects into the plane of the arm 28 of a bell crank lever of which the other arm 27 engages above the projection 24 of the disconnecting rod 21.

50 The operation of the device is the following: When abnormal forces arise the spring pressure of the bolt 30 is no longer capable of retaining the lever 29. This lever therefore rotates on the pivot 41 and moves 55 with it the rib 31. The spindle 39 is thus rotated about its longitudinal axis and the lower arm 34 thereof is moved laterally, and the bell crank lever 35 loses its support so that, in consequence of the spring 60 19, it strikes against the arm 28. With the arm 28 the pawl 27 rotates about 26, being thus raised from the projection 24 of the disconnecting rod 21, and this latter in the known manner puts the press out of operation 65 and applies the brake.

Instead of retaining the three-armed lever, which connects the connecting rod to the roller carriage, in its normal position by wedge-shaped grooves this could be effected by pressing the two members on one another by friction the parts in unstable equilibrium.

In the examples illustrated the putting out of operation and braking of the press is directly effected by the variation of the 75 position of connecting rods, that is, by the variation of the position of the members thereof in relation to one another. The device would, however, also be effective if the fracture of any other part which transmits 80 movement to the roller carriage produces a relative movement, for example, if the platen abuts against the safety device which operates the stopping mechanism as is for example provided as on the roller carriage 85 itself or its path.

Having now particularly described and ascertained the nature of my said invention and in what manner the same is to be performed I declare that what I claim is:— 90

1. In a safety device for platen printing presses, the combination with a roller carriage, of means for reciprocating the carriage including pivotally mounted bars having coacting cam faces arranged to separate 95 said bars upon relative movement of the same longitudinally from their normal position, a spring for holding said bars in coupled relation, throwout mechanism for the press, and a trip device engaging one of said bars 100 and serving upon separating movement thereof to actuate said throwout mechanism, substantially as described.

2. In a safety device for platen printing presses, the combination with a roller carriage, of means for reciprocating the carriage including pivotally mounted bars having coacting cam faces arranged to separate said bars upon relative movement of the same longitudinally from their normal position, a spring for holding said bars in coupled relation, throwout mechanism for the press, and a trip device having a portion 110 thereof mounted on the pivot of one of said bars and engaging the other of said bars 115 and serving upon separating movement of the bars to actuate said throwout mechanism, substantially as described.

3. In a safety device for platen printing presses, the combination with a roller carriage, of means for reciprocating the carriage including connecting bars having coacting cam faces arranged to separate said bars for relative movement of the same longitudinally from their normal position, throwout mechanism for the press, and a trip device held by said bars in their normal position and released thereby when said bars are separated to actuate said throwout mechanism, substantially as described. 120 125 130

4. In a safety device for platen printing presses, the combination with a roller carriage, of means for reciprocating the carriage including coacting cam members with yielding means for holding the same in operative relation and permitting displacement thereof, throwout mechanism for the press, and a trip device arranged to be released from said cam members to actuate

said throwout mechanism, substantially described.

In testimony whereof I have hereunto set my hand in presence of two subscribing witnesses.

MAX ROCKSTROH.
